UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

GAME TABLE.

Application filed November 15, 1926. Serial No. 148,492.

My invention relates to tables and has a special relation to game tables.

One object of the invention is to provide a light-weight game table that may be collapsed and readily stored away and also may be quickly set up for use.

Another object of the invention is to provide a billiard table having a bed which is inexpensive and at the same time strong and durable and will maintain a smooth and satisfactory playing surface.

A further object of the invention is to provide devices for supporting a table, which may be readily collapsed into a minimum of room and may be conveniently restored to the normal position of usage.

A still further object of the invention is to provide a table with simple and inexpensive leveling devices.

Other objects and advantages will appear as the description proceeds. Referring to the accompanying drawings.

Fig. 1 is a bottom plan view of a game table embodying the invention.

Fig. 2 is a side elevational view thereof.

Fig. 3 is an elevational view of a device for securing a pair of table legs to a brace bar, parts being broken away.

Fig. 4 is a detail view of a pivotal support for a table leg.

Fig. 5 is a sectional detail view of a leveling device for a table leg.

Fig. 6 is a sectional view taken on the line 6—6 of Fig. 5.

Fig. 7 is a bottom-plan, detail view of a pivotal support for brace rods, and

Fig. 8 is a vertical sectional view of a table bed and parts co-operating immediately therewith, parts being broken away.

The bed of the table is made of laminations of wood reinforced at their outer surfaces by sheets of metal. In the embodiment shown it comprises two thin outer sheets 1 of metal, thin layers 2 of relatively hard wood adjacent the sheets 1, and relatively thick

layers 3 of relatively soft wood between the layers 2, all of these sheets and layers being secured rigidly together by a waterproof binder such as albumen glue.

The thickness of the bed may vary considerably, thicknesses ranging from three eighths inch to slightly over an inch having

been found practicable. The metal sheets and the layers 2 of hard wood may also vary in thickness. A twenty-four gage metal sheet reinforced by a hard-wood layer of three thirty-seconds inch will not be dented by balls. The number of layers may be more or less than that in the embodiment illustrated.

Table beds such as illustrated have been capable of withstanding attacks of moisture and marked changes in atmospheric conditions without warping or deteriorating and they maintain a smooth playing surface over long periods of time.

By providing plies or laminæ of varying hardness, there is provided a bed in which the under laminæ of relatively soft wood afford a base or foundation which is a relatively soft or yielding support for the top lamina of hard wood. Moreover, the relatively thin metal sheathing which overlies the top lamina affords a comparatively hard and dent-proof top surface. The various laminæ of the bed thus provides a gradation in hardness or resistance upwardly through the bed. It will be understood that all of the wooden laminæ are adhesively secured by an albumen glue binder, which is a preferable type of binder, due to its resistance to moisture. This is an important feature of the construction, since the binder is itself moisture-resistant, although protected by the metal sheathing, which in the preferred form, is applied to both the top and bottom surfaces. The sheathing and binder assist the laminated wood construction in resisting and minimizing warping.

It will be further observed that the metal sheathing covering the top wood lamina is continuously secured to the surface of the wood by an adhesive, thus avoiding air pockets between the wood and metal, and providing a top metal lamina which is in intimate contact with the hard wood lamina therebeneath throughout the meeting faces of the two laminæ.

A cloth 4 which covers the bed provides a playing surface and may be secured to the layers of wood by suitable retainers such as tacks 5. The bed may be secured to strips 6 underlying the rails 7 by means of bolts 8 extending directly through the bed and received in bushings 10 embedded in the strips

6 but it will be understood that the rails 7 may be of various shapes and the strips 6 may be integral with the rails.

The bed may be supported by similar pairs 5 of pivoted legs.

A leg 11 similar to the others may be of tubular form, a means for pivotally securing it to the bed is shown in detail in Fig. 4 and may comprise a plug 12 which may be secured 10 within the leg 11 by being forced there-in and may have a pair of lugs 13 thereon pivotally mounted on a pin 14 which may be carried by a support 15 on a plate 16. The plate may be secured directly to the bed by means 15 of screws 17.

The leg 11 may be rigidly secured to a leg, 18 by means of a cross bar 19.

The legs 11 and 18 may be swung about 20 their pivot points to collapse the table or 20 to place them in a position to support the bed.

They may be held in the latter position by 25 means of a brace rod 20 which may have a flattened and curved end 21 for gripping the cross bar 19. A yoke 22 may be loosely mounted on the cross bar 19 and prevented from moving longitudinally thereon by 30 means of pins 23 on the cross bar. A thumb screw 24 may extend through the yoke and engage the end of the brace rod and prevent its accidental release. By loosening the thumb screw 24 and swinging the yoke 22 downwardly the end of the brace rod may be 35 disengaged from the cross bar.

The other end of the brace rod may be 35 pivoted on a pin 25 supported by lugs 26 depending from a plate 27 which is secured to the bed.

The pin 25 may also pivotally support a 40 brace rod 28 which may serve after the manner of the brace rod 20 for bracing an additional pair of legs.

When the legs are collapsed, the brace rods may be swung to a position adjacent the bed 45 so that the table may be made to occupy a minimum of room.

Each table leg may be provided with a levelling device, (Figs. 5 and 6). It may comprise a nut 29 which may extend into the 50 lower end of the leg and may receive a screw 30 having a head 31 thereon. The head may have holes 32 therein to facilitate the turning thereof and may have a boss or protuberance 33, thereon and a laterally directed flange 34. The lower end of the head 31 may be received within a cup-like base or foot 35 which the boss or protuberance may engage. A retaining ring, 36 may be provided in a recess 37 for preventing accidental detachment 60 of the base or foot. The engagement of the flange 34 with the retaining ring will prevent separation of parts but the retaining ring will permit free relative rotary movement of parts so that the head 31 may be 65 moved readily in leveling the table. The boss

or protuberance will also facilitate turning of the head 31.

The invention is not limited to the specific details of construction of the embodiments illustrated and described, but is capable of 70 extensive modifications. A substantial range of equivalents is contemplated within the spirit of the invention and the scope of the appended claims.

I claim:

1. A game table having a bed composed of laminations of wood secured together by an adhesive and having sheets of metal covering the outer surfaces of the laminated structure and secured thereto by an adhesive, said 80 bed being in a single unit having an uninterrupted playing surface, cushions at the sides of said bed and supporting legs secured directly to said bed.

2. A game table having a bed composed of 85 laminations of wood secured together by an adhesive and having sheets of metal covering the outer surfaces of the laminated structure and secured thereto by an adhesive, rails secured to said bed and legs secured directly 90 to said bed and supporting said bed and said rails.

3. A game table having a bed composed of 95 laminations of wood secured together by an adhesive and having sheets of metal covering the outer surfaces of the laminated structure and secured thereto by an adhesive, a pair of legs, each pivoted to said bed, a cross bar rigid with said legs and a stay rod pivoted to said bed and detachably secured to said 100 cross bar.

4. In a game table of the billiard type, a bed comprising laminæ of wood adhesively secured together with the top lamina relatively harder than an under lamina, and a permanent fabric playing surface covering said top lamina.

5. In a game table of the billiard type, a bed comprising laminæ of wood adhesively secured together, a relatively thin sheet of 105 metal continuously secured to and covering the top lamina, and a permanent fabric playing surface covering said metal.

6. In a game table of the billiard type, a bed comprising laminæ of wood adhesively secured together and a relatively thin sheet of 110 metal covering the top lamina and adhesively secured thereto.

7. In a game table of the billiard type, a bed comprising laminæ of wood adhesively secured together, the top lamina being relatively harder than an under lamina, and a relatively thin sheet of metal covering the 115 top lamina.

8. In a game table of the billiard type, a bed comprising laminæ of wood adhesively secured together, the top lamina being relatively harder than an under lamina, and a relatively thin sheet of metal covering the 120 top lamina and adhesively secured thereto.

9. In a game table of the billiard type, a bed comprising laminæ of wood adhesively secured together, relatively thin metal continuously secured to and covering the outer 5 laminæ, and a permanent fabric playing surface covering the top lamina.

10. In a game table of the billiard type, a bed comprising laminæ of wood adhesively secured together, relatively thin metal covering the outer laminæ and adhesively secured thereto, and a permanent fabric playing surface covering the top lamina.

11. In a game table of the billiard type, a bed comprising laminæ of wood adhesively secured together, the top lamina being relatively harder than an under lamina, and relatively thin metal covering the outer laminæ.

12. In a game table of the billiard type, a bed comprising laminæ of wood adhesively

secured together, the top lamina being relatively harder than an under lamina, and relatively thin metal covering the outer laminæ and adhesively secured thereto.

13. In a game table of the billiard type, a bed comprising laminæ of wood, waterproof adhesive securing said laminæ together, the top lamina being relatively harder than an under lamina, and a permanent fabric playing surface covering said top lamina.

14. In a game table of the billiard type, a bed comprising laminæ of wood, waterproof adhesive securing said laminæ together, the top lamina being relatively harder than an under lamina, a relatively thin sheet of metal adhesively secured to and covering the top 35 lamina, and a permanent fabric playing surface covering said top lamina.

JOSEPH W. BISHOP.
